US00D333121S

United States Patent [19]

Craveiro

[11] Patent Number: Des. 333,121

[45] Date of Patent: ** Feb. 9, 1993

[54] CONNECTOR CLAMP FOR USE WITH
BATTERY TERMINALS OF DIFFERING
TYPES

[75] Inventor: Joseph C. Craveiro, Costa Mesa,
Calif.

[73] Assignee: American Consolidated Enterprises,
Inc., Trabuco Canyon, Calif.

[**] Term: 14 Years

[21] Appl. No.: 348,025

[22] Filed: May 5, 1989

[52] U.S. Cl. D13/120; D13/149

[58] Field of Search D13/120, 149; 439/502,
439/504, 507, 754, 755, 756, 760, 822

[57] CLAIM

The ornamental design for a connector clamp for use with battery terminals of differing types, as shown and described.

DESCRIPTION

FIG. 1 is a front respective view of a connector clamp for use with battery terminals of differing types showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.

FIG. 1

FIG. 2

FIG. 3

FIG. 4

FIG. 5

FIG. 6

FIG. 7
